UNITED STATES PATENT OFFICE

PAUL A. MEEHAN, OF CLEVELAND, OHIO, ASSIGNOR, BY MESNE ASSIGNMENTS, TO SWINDELL-DRESSLER CORPORATION, OF PITTSBURGH, PENNSYLVANIA, A CORPORATION OF PENNSYLVANIA

KILN CAR

Application filed April 23, 1929. Serial No. 357,438.

The present invention relates to the construction and mode of operation of kiln cars or trucks such as are employed in moving material to be subjected to heat treatment through a continuous tunnel kiln. In practice a plurality of such cars are arranged in a train which normally fills the kiln and which is periodically advanced a car length at a time to permit additional cars to be successively inserted at the entrance end of the kiln by a suitable car pushing mechanism which ordinarily engages the rear car of the train. The forward car of the train is moved during each periodic movement into an exit chamber, from which it is passed externally of the kiln and the material heat treated unloaded. Usually the car moving force is transmitted between adjacent cars by having their adjacent ends in contact.

In recent years the width of kilns of this type has been substantially increased with a corresponding increase in width and wheel gauge of the material carrying cars. No proportionate increase in the length of the cars has accompanied this increase in car wheel gauge and the ratio of the car wheel base to the wheel gauge is now disproportionately large. By way of illustration and not of limitation, a kiln car of the type to which my invention is especially applicable, has a width of 7'-0", a length of 5'-3", a wheel gauge of approximately 4'-2", and a wheel base of 3'-1". When a train of such cars is periodically moved by pusher mechanism, there is a highly disadvantageous tendency for adjacent cars in the train to be moved out of longitudinal alignment i. e. for each car to be slightly turned about its vertical axis. This movement results in increased friction between the car wheel flanges and tracks at diagonally opposite points on the car, causing increased wear on the parts and an increase in the amount of power consumed by the car moving mechanism.

The object of my present invention is to provide simple and effective means by which adjacent kiln cars can be centered on the supporting tracks and maintained in longitudinal alignment without requiring any

change in the normal method of handling the cars.

The various features of novelty which characterize my invention are pointed out with particularity in the claims annexed to this specification. For a better understanding of the invention, however, and the advantages possessed by it, reference should be had to the accompanying drawing and descriptive matter in which I have illustrated and described a preferred embodiment of the invention.

Of the drawing:

Fig. 1 is a horizontal section through a portion of a tunnel kiln containing kiln cars embodying my invention;

Fig. 2 is a vertical section on the line 2—2 of Fig. 1; and

Fig. 3 is a horizontal section on the line 3—3 of Fig. 2.

In the conventional kiln illustrated in Fig. 1, A represents the kiln proper and B, the stationary track rails positioned along the bottom of the kiln chamber A'. A plurality of kiln cars or trucks C arranged in a train which normally fills the kiln and which is periodically moved longitudinally of the kiln in the direction indicated by the arrow in Fig. 1 by car pushing mechanism normally positioned adjacent the entrance end of the kiln. Each kiln car comprises a metallic frame D forming the bottom of the car body and preferably made as a one piece casting of a suitable metal, such as semi-steel. The car frame has a rectangular bottom surface formed with upstanding side and end marginal flanges D' and D², respectively. The portion of the frame within the marginal flanges is formed with a plurality of upstanding ribs extending transversely and longitudinally of the frame.

In practice the frame is filled with a layer of concrete, on which refractory blocks and girders are positioned. A refractory platform, on which the ware to be heat treated is supported, is mounted on the girders. Such ware supporting arrangements are now well known in the art and illustration herein is unnecessary.

At symmetrically arranged points adjacent

each corner of the frame 1, wheel mountings E are provided, each of which comprises spaced apart depending flange members E', formed with a slot E² open at its lower end 5 to provide a seat for a stationary wheel axle F. Circumferentially flanged wheels G are rotatably mounted on the axles F. A vertical sand seal plate H secured by bolts H' depends from each of the side flanges D' 10 throughout the length thereof and is arranged to extend into a stationary sand trough (not shown) extending longitudinally at each side of the kiln chamber. The gas seal effected by this arrangement prevents the 15 heated kiln atmosphere from directly contacting with the underside of the kiln car with consequent deterioration and destruction of the wheels and wheel mountings. The underside of the car frame is formed with a 20 depending transverse flange D³ arranged at the rear end of the car and extending on each side of the longitudinal center line thereof. This flange is relatively thick and inwardly spaced from the corresponding upstanding 25 flange D².

As shown particularly in Figs. 1 and 2, the desirable position of the kiln cars on the track B is with their side edges in longitudinal alignment, the load equally distributed 30 on the axles, and the marginal end flanges D² of adjacent cars contacting with one another. In this position of the cars, the ends of adjacent sand seal plates are in contact and prevent the leakage of the kiln atmosphere 35 between the cars. In carrying out the object of my invention I provide means mounted on the car for aiding in centering the cars relative to one another and maintaining them in their centered position. In 40 the construction shown such means consist of co-operating devices on each end of the cars and particularly, as illustrated in the drawing, of a projecting pin or tongue K mounted on the rear end of each car received 45 in a guide box M arranged on the front end of the succeeding car.

The projecting pin K is preferably of forged steel and in form comprises an enlarged head portion K' and a body K² positioned in a passage D⁴ at the center of the flange D³. The front end of the head K' contacts with the rear side of the flange D³ and the remaining portion of the head is tapered rearwardly in height and width. The body of the pin is positioned horizontally in the passage D⁴ and formed with a reduced threaded end K³. The pin is maintained with its head in contact with the flange D³ by a nut N on the threaded end K³ and locked in position by a cotter pin N' as 50 shown in Fig. 2. The front end of the pin head is formed with a flat upper surface K⁴, which by its contact with a projecting portion D⁵ of the flange D³ prevents rotation of 55 the pin in its mounting.

The guide box M, which is arranged to receive the tapered head of the centering pin, is removably mounted on the front end of each car below the bottom surface of the frame and extends on each side of the longitudinal center line of the car. The guide box comprises an inverted channel shaped body portion M', the front end of which is substantially flush with the outer side of the adjacent marginal flange D². The passage 70 M² formed by the sides of the guide box body is tapered rearwardly as shown in Fig. 3 with a taper corresponding to that of the sides of the pin head. The top of the box body is inclined rearwardly at an angle corresponding to the top surface of the pin head. As shown in Fig. 3 the front portion of each car frame is formed with longitudinally extending flanges D⁶ which are spaced apart to receive the guide box M therebetween. The guide box is formed with a pair of laterally projecting flanges M³ arranged to contact with the front end of the flanges 85 D⁶ and secured thereto by cap screws M⁴. 90

With the kiln cars constructed and arranged in the kiln as described, a car is periodically moved into the kiln chamber at the entrance end thereof until its front marginal flange D² contacts with the rear marginal flange D² of the rear car of the train. 95 During this periodic movement the guide box on the car receives the tapered head of the centering pin on the rear end of the last car in the chamber. The centering pin and guide box are so tapered that an entry of the pin is possible under all normal operating conditions. Suitable clearance between the top surface of the pin and underside of the guide box body top provides for slight variations in the heights of the engaging cars and contacting parts. With the projecting pins of each car positioned in the guide box of the following car, and the pin and guide box being preferably symmetrical with the longitudinal center lines of the cars, any tendency of the forward car of each pair of adjacent cars to move laterally relative to the rear car of the pair will be prevented by the guide box of the latter holding the projecting pin of the former. This lateral movement prevention effect increases with the length of the projecting portion of the pin. Lateral movement of the rear car of the pair relative to the forward car is prevented by the pin K contacting with the sides of the guide box. In effect, each car in the train, except the end cars, is held in its proper position on the track by the adjacent cars at its front and rear and the car moving mechanism moves the train as a unit. 110 115 120 125 130

In operating kilns of this character, it is customary to remove the foremost goods carrying car from the kiln exit chamber immediately after the periodic train movement. Means for this purpose generally comprise 135

a pulling device adapted to engage the front end of the car. Each of the car centering devices described is arranged with means which may be engaged by such pulling device. As shown in Figs. 2 and 3, a vertical passage K^5 is formed in the head of the centering pin K , the upper and lower ends of the passage being enlarged to facilitate the engagement of the pulling device. The opposite end of the car is also provided with means for this purpose, which consists of a transverse pin R . The pin is cast into position between the flanges D^6 at a point adjacent to and in the rear of the guide box M and the open bottom of the guide box and tapered sides aid in the engagement of the pulling device.

My invention is particularly characterized by the simplicity and effectiveness of the car movement preventing or centering provisions disclosed, by the prevention of excessive wear on certain car elements and leakage between the ends of the sand seal plates, by an increase in effectiveness of the car moving mechanism, by the free separation of the centering provisions under tension, and by the low initial and replacement costs of the centering provisions.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. In a tunnel kiln comprising an elongated kiln chamber, a plurality of kiln cars movable longitudinally therethrough, under the action of a car pushing mechanism, said cars being formed at their ends with surfaces extending substantially the full width of the cars, the said surfaces at adjacent ends of each adjacent pair of cars being arranged to transmit substantially all of the force through which the cars in advance are moved and to seal the joint between the cars, and means for preventing relative lateral movement of adjacent cars in said kiln chamber comprising cooperating devices at adjacent ends of said cars.

2. In a tunnel kiln comprising an elongated kiln chamber, a plurality of kiln cars having a wheel gauge substantially as great as the car wheel base and movable longitudinally therethrough under the action of a car pushing mechanism, said cars being formed at their ends with surfaces extending sub-

stantially the full width of the cars, the said surfaces at adjacent ends of each adjacent pair of cars being arranged to transmit substantially all of the force through which the cars in advance are moved and to seal the joint between the cars, and means automatically operating to prevent relative lateral movement of adjacent cars in said kiln chamber while permitting the separation thereof under tension comprising cooperating devices at adjacent ends of said cars.

3. In a tunnel kiln comprising an elongated kiln chamber, a plurality of kiln cars movable longitudinally therethrough under the action of a car pushing mechanism, said cars being formed at their ends with surfaces extending substantially the full width of the cars, the said surfaces at adjacent ends of each adjacent pair of cars transmitting substantially all of the force through which the cars in advance are moved and sealing the joint between the cars, and means for preventing lateral movement of said cars in said kiln chamber comprising overlapping longitudinally extending surfaces at the adjacent ends of adjacent cars.

4. In a tunnel kiln comprising an elongated kiln chamber, a plurality of kiln cars movable longitudinally therethrough under the action of a car pushing mechanism, said cars being formed at their ends with surfaces extending substantially the full width of the cars, said surfaces at adjacent ends of each adjacent pair of cars being arranged to transmit substantially all of the force through which the cars in advance are moved and to seal the joint between the cars, and means for preventing lateral movement of said cars in said kiln chamber comprising a pair of separately formed cooperating members having overlapping longitudinally extending surfaces and mounted at the adjacent ends of adjacent cars.

5. A tunnel kiln car adapted to be moved in a train through a kiln under the action of a car pushing mechanism and comprising a pair of vertical flanges extending substantially throughout and forming the front and rear marginal portions thereof and arranged in use in pushing contact along their length with corresponding flanges on adjoining cars, and means for maintaining said car in rigid longitudinal alignment with said adjoining cars while moving through the kiln comprising a tapering guide member at one end of said car, and a member forming a tapering guide socket at the opposite end of said car and in the same horizontal plane as said guide member, the guide member on each car being arranged to fit within the guide socket on an adjoining car.

6. A tunnel kiln car adapted to be moved in a train through a kiln under the action of a car pushing mechanism and comprising a pair of vertical flanges extending substan-

5 tially throughout and forming the front and rear marginal portions thereof and arranged in use in pushing contact along their length with corresponding flanges on adjoining cars, and means for maintaining said car in rigid longitudinal alignment with said adjoining cars while moving through the kiln comprising a tapering guide member at one end of said car below the corresponding marginal flange, a member forming a tapering guide socket at the opposite end of said car below the corresponding marginal flange and in the same horizontal plane as said guide member, both of said members being symmetrical 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255
